UNITED STATES PATENT OFFICE

WILLIAM H. LOLLEY, OF NEW YORK, N. Y.

LIFTING JACK

Application filed November 12, 1926. Serial No. 147,907.

This invention relates to lifting jacks, and more especially to jacks for raising automobiles.

The advent of balloon tires has made it necessary to provide jacks which, when in their collapsed state, will be of relatively low height, so that the jack can be readily placed below the axle of an automobile, which has dropped due to a puncture in the balloon tire.

Jacks having comparatively low vertical dimensions when in their collapsed state have previously been proposed, such jacks being operated to effect the raising of the upper end thereof by means of a screw-threaded rod engaging spaced nuts pivotally connected to levers arranged somewhat in the form of lazy tongs. In such jacks, the force for actuating same is applied in a horizontal direction, and it is only the vertical component of this force which is useful in effecting the operation of the jack. This vertical component is comparatively small when the jack is in its collapsed condition, and is comparatively great when the jack is in its extended position; while, in such jacks, the amount of vertical movement corresponding to the horizontal movement of the pivotal points of the lazy tong levers is much greater during the initial operation of the jack when in its lowermost position, than during the final operation thereof when in its extended position. It is thus obvious that the force applied to the jack for operating the same must be very considerably greater during the initial operation thereof, than during the final operation.

The primary object of the present invention is to provide a jack in which this disparity in the amount of force to be applied at the commencement and at the end of the operation thereof is practically avoided.

With this object in view, the lifting jack comprises a pair of levers pivotally mounted at their lower ends, a rest supported on such levers, means for turning said levers about their pivots, and means intermediate said levers and the rest, whereby a substantially uniform vertical movement will be imparted to said rest for a uniform horizontal com-

ponent of the movement of the upper ends of said pivoted levers.

Further features of the invention are brought out in the accompanying description, and are particularly set forth in the accompanying claims.

In order that the invention may be clearly understood, reference is made to the accompanying drawings, which illustrate, by way of example, two embodiments of the invention, and in which:—

Figure 1 is a front elevation of one embodiment of my invention showing the jack in extended condition in full lines and in collapsed condition in dotted lines;

Fig. 2 is a side elevation of the jack in its extended condition;

Fig. 3 is a front elevation of a preferred embodiment of my invention showing the jack in collapsed condition and giving a diagrammatic illustration of the rise per each four revolutions of the operating screw;

Fig. 4 is a side elevation of the upper part of the jack illustrated in Fig. 3 when in its extended condition;

Fig. 5 is a side elevation of the upper part of a jack in its collapsed condition illustrating means for stabilizing the rest.

The embodiment of the invention illustrated in Figs. 1 and 2 of the drawings comprises a pair of levers 1 and 2 preferably crossed, as shown, at their lower portions and pivoted at their lower ends to pivots 3 and 4 respectively, such pivots being respectively mounted in lugs 5 and 6 extending upwardly from a base plate 7. The base plate 7, with the upstanding lugs 5 and 6, may be cast, if desired, but preferably it is stamped from sheet metal, the lugs being cut from said metal and then bent upwardly.

The levers 1 and 2 are pivotally connected preferably at their upper ends to members 8 and 9. These members may both be screw-threaded nuts, though as shown in Fig. 1 one of such members, 8, comprises a bearing for the end of the screw-threaded operating shaft 10, and the other of such members 9, forms a screw-threaded nut which engages on said screw-threaded operating shaft 10. Any suitable means may be provided for ac-

tuating the screw-threaded operating shaft 10, such means preferably comprising a handle preferably of considerable length, connected to the end of said operating shaft by means of a universal joint.

Any suitable means are provided for ensuring that the levers 1 and 2 will turn about their pivots equal amounts when the operating shaft 10 is actuated. In the embodiment illustrated in the drawings, such means comprises a pin 13 mounted intermediate the ends of the lever 2, and operating in a suitably shaped slot 14 provided in the lever 1.

Pivottally connected at their lower ends to the members 8 and 9, or to the upper portions of the crossed levers 15 and 16, are two crossed levers 15 and 16. These crossed levers are not pivottally connected together, but the free ends of such levers are adapted to rest respectively upon members 18 and 17 mounted respectively intermediate the ends of such lever, such members being preferably in the form of rollers pivottally mounted on such levers. Said levers 15 and 16 at the portions thereof which engage the members 18 and 17 are respectively provided with cam surfaces 19 and 20, the cam surface 19 on the lever 15 being adapted to engage the member 18 on the lever 16, and the cam surface 20 on the lever 16 being adapted to engage the member 17 on the lever 15. The cam surfaces 19 and 20 are preferably provided on the inner edges of the levers 15 and 16, though, if desired, they may form the upper sides of slots provided respectively in the levers 15 and 16.

Resting on the outer portions of the levers 15 and 16 is a rest 21. This rest in the embodiment illustrated in Figure 1 is provided with members 22 and 23 which respectively engage cam surfaces 24 and 25 on the levers 15 and 16 respectively. The members 22 and 23 may be in the form of rollers, as shown pivottally mounted on said rest, though, if desired, they may comprise ridges or the like projecting downwardly from the under surface of the rest 21 or may be dispensed with in which case the under surface of the rest will rest directly upon the cam surfaces. The cam surfaces 24 and 25 may be provided on the outer edges respectively of the levers 15 and 16, though, if desired, they may form the lower sides of slots provided in said levers 15 and 16 respectively.

If the cam surfaces 24 and 25 form the lower sides of slots in the levers 15 and 16 respectively, the members 22 and 23 would be in the form of pins and rollers, and the upper sides of the slots would engage the upper sides of such pins or rollers, and would thus help to stabilize the rest 21 in its position on the levers 15 and 16.

In order to prevent any possibility of a rocking or horizontal movement being imparted to the rest 21, when a weight is sup-

ported thereon, such rest is provided with depending arms 26 which embrace the levers 15 and 16, one or both of such arms being provided with a vertical slot 27, in which a pin or pins 28 is or are adapted to operate. Each pin 28 extends outwardly from and forms the pivotal point of a pair of links 29, 30, the free ends of which are pivotally connected respectively to the levers 15 and 16. Such links in the embodiment illustrated are provided intermediate the levers and the depending arm or arms 26.

Each of the levers 1, 2, 15 and 16 comprises spaced side members 1^a, 1^b; 2^a, 2^b; 15^a, 15^b; and 16^a, 16^b respectively, which are held rigidly in spaced relation with each other by any suitable means, preferably by means of transverse webs 31 extending therebetween. The lever 1 is located between the spaced side members 2^a, 2^b, of the lever 2, the transverse webs 31 in the two levers being so positioned as not to interfere with the full extent of the relative movement between the two levers. The lever 15 extends between the side plates 16^a, 16^b, of the lever 16, the transverse webs 31 in such levers being so positioned as not to interfere with the relative movement of said levers.

In order to increase the stability of the jack when in its extended position, the side plates of the lever 15 are each provided with an open-ended slot 33, in which a pin 32, mounted between the side plates of the lever 16, is adapted to be positioned when the jack is extended to its maximum amount.

The embodiment of the invention illustrated in Figs. 3 and 4 of the drawings operates upon the same principle as that illustrated in Figs. 1 and 2 of the drawings and comprises the lower pivoted levers 1 and 2 and the upper pivoted levers 15 and 16 which rest respectively upon the rollers 18 and 17. The raising and lowering of the jack is effected by means of the screw threaded rod 10 which in the embodiment illustrated is provided with left and right hand threads 10^a, 10^b which operate respectively in nuts 8^a and 9^a located at the points where the upper ends of levers 1 and 2 are pivoted to the lower ends of levers 15 and 16.

The important feature of difference between the construction according to this embodiment and that illustrated in Figs. 1 and 2 of the drawings comprises the means for effecting the steadyng of the rest 21 which, as in the embodiment previously described, rests upon the upper free ends of the pivoted levers 15 and 16. The means for steadyng the rest 21 in the present construction comprises, as in the former construction, a plurality of links pivoted together at their upper ends by the pin 28 and pivoted respectively at their lower ends to the levers 15 and 16. These links, however, instead of being disposed in planes between the outer faces

of the levers 15 and 16 and the depending arms embracing such levers as in Fig. 2, are provided substantially in the vertical central plane of the jack and preferably comprise a single link 30 pivoted at its lower end to the lever 16 and two links 29^a and 29^b on opposite sides of said link 30, which are pivoted at their upper ends to the link 30 and at their lower ends to the lever 15 as illustrated in Fig. 4. The pin forming the pivotal connection to the upper ends of the links extends between vertical slots 27^a in the two arms 26^a depending from the lower face of the rest 21 between the side members of the links 15 and 16 and embracing said links 29^a, 29^b and 30.

The lower ends of the links 29^a, 29^b and 30 are preferably pivotally mounted on pins 17^a and 18^a extending respectively between the side members of the levers 15 and 16 which pins preferably form the pivots for the rollers or the like 17 and 18 which engage the cam surfaces 20 and 19 respectively. Such links 29^a, 29^b and 30 are maintained in definite spaced relation between the side members of the levers by any suitable means such as collars mounted on said pins 17^a and 18^a and extending between such side members and the links.

In the construction according to the second embodiment, the rest 21 is provided with downwardly extending portions 21^a and 21^b which embrace the links 15 and 16.

Also in the construction according to the second embodiment, the stabilizing means comprising the open-ended slot 33 and pin 32 illustrated in Fig. 1 of the drawings is omitted, since such means are not essential for giving stability to the jack according to such construction.

Referring to the embodiment illustrated in Fig. 5 of the drawings, the depending side portions 26 of the rest 21 are not provided with vertical slots, but these side portions adjacent their outer edges support pins 36, 37 extending between such side portions and through slots 38, 39 provided in the outer ends of the upper levers 16 and 15 respectively. These slots are of such shape that during the raising of the rest the pins 36 and 37 will respectively slide therein.

Such means will prevent the lifting of the rest relatively to the upper levers but would not prevent side movement of the rest. In order to prevent this side movement one or more depending members 40 are provided which extend downwardly from the under surface of the rest. The side faces 41, 42 of these depending members are of the contour illustrated in the drawing, such contour being designed so that said side members will engage against pins 43, 44 or the like extending between the side members of the upper levers and forming the pivots for the

members 17 and 18, throughout the complete operation of the jack.

The depending members 40 are recessed at 45 and 46 at their upper portions so that they will permit full extension of the jack even though the side members of the upper levers 15 and 16 are connected at their outer ends by webs 47, 48.

By such means both vertical and horizontal stability of the rest is insured.

Mounted on the upper face of the rest is a bearing member 49 of special form.

The essential feature of this bearing member is that it extends transversely of the rest and has an upper face or faces of arcuate form extending in such transverse direction. In the form illustrated in Figs. 3 and 4 of the drawings, this bearing member is of U-shaped form having upstanding side portions 50 and 51. The base 52 of this member rests upon the upper face of the rest and is connected thereto by any suitable means such as riveting, with the said side portions 50 and 51 extending transversely of the rest. As clearly shown in Fig. 4 of the drawings, the upper edges of each of said side members are of arcuate form.

The great advantage of a bearing member of this type is that the load will always rest upon the jack intermediate the side edges of the rest and thus the line of support will always lie well within the upper face of the rest and side strain on the jack will be reduced very appreciably. This is of special importance when the jack is placed under the axle of an automobile since the raising of the car will cause a tilting of the axle in which case, unless special means were provided as in the present case, the axle would rest upon the inner edge of the rest and considerable side strain would be placed upon the rest.

A further advantage of the bearing member is that the contact between the bearing member and the load will always be more than point contact which, of course would occur between a tilted axle and the corner of the rest if the rest were not provided with special bearing means to obviate such disadvantage; thus the tendency to slip between the load and the jack will be minimized. In order to further minimize such tendency to slip the upper arcuate edges of the bearing member may be serrated as illustrated in Fig. 4 of the drawings.

The bearing member could be constructed in other forms than that illustrated, for instance the two side members may be independent of each other and connected to the rest separately or they may be stamped out from the upper face of the rest. Also the bearing member may have one broad bearing face of arcuate form instead of the two bearing edges in the form illustrated.

The operation of the jack is as follows:

When the handle connected to the shaft 10 is operated and the screw-threaded shaft 10 thereby turned, the levers 1 and 2 are turned about their pivots 3 and 4 respectively, the upper ends of said levers being drawn together and raised. The lower ends of the levers 15 and 16 are also drawn together but during the initial movement of the jack there will be very little turning movement of the levers 15 and 16 about their pivots, since the outer portions of the cam surfaces 20 and 19 are so formed that they will merely slide on the members 17 and 18 without tending to turn the levers upon which they are formed to any appreciable extent about their pivots. As the operation of the jack is continued and the members 8 and 9 are drawn closer together, the inner portions of the cam surfaces 19 and 20 will engage the members 18 and 17 respectively and owing to the special form of such inner portions of the cam surfaces, pivotal movement of the levers 15 and 16 will be effected and then gradually increased. The cam surfaces 24 and 25 on the upper sides of the levers 15 and 16 are of a known type being so shaped as to exert a gradually increasing vertical movement to the rest 21 as the actuation of the jack continues beyond a certain point, the shape of such cam surfaces also being such that up to such point they do not exert any lifting movement on the rest 21 apart from that which is caused by the upward movement of the levers 15 and 16 as a whole. The shapes of the two pairs of cam surfaces 19 and 20, and 24 and 25 are so designed that for equal horizontal movement of the members 8 and 9 towards each other, that is for equal amounts of rotation of the screw-threaded operating shaft 10 substantially equal vertical movement will be imparted to the rest 21.

The links 29 and 30 will not interfere with the relative movement of the levers 15 and 16; they will operate merely to stabilize the rest 21.

The embodiments of the invention herein referred to are given merely by way of illustration, and it is understood that the various parts of the apparatus described herein may be modified without departing from the spirit and scope of the invention as indicated in the appended claims.

What I claim is:—

1. A lifting jack comprising a base member, a pair of levers pivotally mounted at their lower ends to said base member, a pair of upper crossed levers pivotally connected at their lower ends to the lower pair of levers respectively, means for turning said lower pair of levers about their pivots, a rest, means on said upper crossed levers for supporting said rest, and means on each upper crossed lever for engaging the other upper crossed lever for effecting the raising of the upper

ends of said upper levers whereby the turning of said lower pair of levers about their pivots will give to the rest a substantially uniform vertical movement for a uniform horizontal component of the movement of the upper ends of the lower levers. 70

2. A lifting jack comprising a base member, a pair of levers pivotally mounted at their lower ends to said base member, a pair of upper crossed levers pivotally connected at their lower ends to the lower pair of levers, means on each upper lever in slidable engagement with the other upper lever for supporting the free ends of such levers, a rest, means for supporting said rest on said upper levers, and means for turning said lower pair of levers about their pivots. 75

3. A lifting jack comprising a base member, a pair of levers pivotally mounted at their lower ends to said base member, a pair of upper crossed levers pivotally connected at their lower ends to the free ends of the lower pair of levers, means on each upper lever in slidable engagement with the other upper lever for supporting the free ends of such levers, a rest, means on said rest in slidable engagement with the upper levers for supporting said rest on said upper levers, and means for turning said lower pair of levers about their pivots. 80

4. A lifting jack comprising a base member, a pair of levers pivotally mounted at their lower ends to said base member, a pair of upper crossed levers pivotally connected at their lower ends to the free ends of the lower pair of levers, means on each upper lever intermediate its ends in slidable engagement with the other upper lever for supporting the free ends of such levers, a rest, means on said rest in slidable engagement with the upper levers for supporting said rest on said upper levers, and means for turning said lower pair of levers about their pivots. 85

5. A lifting jack comprising a base member, a pair of levers pivotally mounted at their lower ends to said base member, a pair of upper crossed levers pivotally connected at their lower ends to the free ends of the lower pair of levers, means for turning said lower pair of levers about their pivots, a rest, means for supporting said rest on said upper levers, a cam surface on each of said upper levers, and means on each upper lever intermediate its ends adapted to engage said cam surface on the other upper lever for supporting said upper levers, whereby the turning of said lower pair of levers about their pivots will give to the rest a substantially uniform vertical movement for a uniform horizontal component of the movement of the upper ends of the lower levers. 90

6. A lifting jack comprising a base member, a pair of levers pivotally mounted at their lower ends to said base member, a pair of upper crossed levers pivotally connected

at their lower ends to the free ends of the lower pair of levers, means for turning said lower pair of levers about their pivots, cam surfaces on the upper edges of said upper levers, a rest, means on said rest for supporting said rest on said cam surfaces, a cam surface on the lower edge of each of said upper levers, and means on each upper lever intermediate its ends adapted to engage said cam surface on the other upper lever for supporting said upper levers, whereby the turning of said lower pair of levers about their pivots will give to the rest a substantially uniform vertical movement for a uniform horizontal component of the movement of the upper ends of the lower levers.

7. A lifting jack comprising a base member, a pair of levers pivotally mounted at their lower ends to said base member, a pair of upper crossed levers pivotally connected at their lower ends to the free ends of the lower pair of levers, means for turning said lower pair of levers about their pivots, cam surfaces on said upper levers, a rest, means on said rest for supporting said rest on said cam surfaces, a second cam surface on each of said upper levers, and means on each upper lever intermediate its ends adapted to engage said second cam surface on the other upper lever for supporting said upper levers, whereby the turning of said lower pair of levers about their pivots will give to the rest a substantially uniform vertical movement for a uniform horizontal component of the movement of the upper ends of the lower levers.

8. A lifting jack comprising a base member, a pair of levers pivotally mounted at their lower ends to said base member, a pair of upper crossed levers pivotally mounted at their lower ends to the lower pair of levers respectively, means for turning said lower pair of levers about their pivots, means for ensuring that the lower pair of levers turn about their pivots equal amounts, a rest, means on said upper crossed levers for supporting said rest, and means on each upper crossed lever for engaging the other crossed lever for effecting the raising of the upper ends of said upper levers whereby the turning of said lower pair of levers about their pivots will give to the rest a substantially uniform vertical movement for a uniform horizontal component of the movement of the upper ends of the lower levers.

9. A lifting jack comprising a base member, a pair of levers pivotally mounted at their lower ends to said base member, a pair of upper crossed levers pivotally mounted at their lower ends to the lower pair of levers respectively, means for turning said lower pair of levers about their pivots, means for ensuring that the lower levers turn about their pivots equal amounts, a rest, means on said upper crossed levers for supporting said rest, means associated with said rest for maintain-

ing same in a substantially horizontal position, and means on each upper crossed lever for engaging the other crossed lever for effecting the raising of the upper ends of said upper levers whereby the turning of said lower pair of levers about their pivots will give to the rest a substantially uniform vertical movement for a uniform horizontal component of the movement of the upper ends of the lower levers.

10. A lifting jack comprising a base member, a pair of levers pivotally mounted at their lower ends to said base member, a pair of upper crossed levers pivotally connected at their lower ends to the free ends of the lower pair of levers, means on each upper lever intermediate its ends in slidable engagement with the other upper lever for normally supporting the free ends of such levers, a rest, means on said rest in slidable engagement with the upper levers for supporting said rest on said upper levers, a pair of links pivotally connected together and pivotally connected respectively to said upper crossed levers, a depending arm extending from said rest having a vertical slot therein, a pin extending from the pivotal point of said pair of links and adapted to slide within said slot in said depending arm, and means for turning said lower pair of levers about their pivots.

11. A lifting jack comprising a base member, a pair of levers, each having spaced sides connected by webs, mounted at their lower ends to said base member, a pair of upper crossed levers, each having spaced sides connected by webs, pivotally connected at their lower ends to the free ends of the lower pair of levers, means on each upper lever intermediate its ends in slidable engagement with the other upper lever for supporting the free ends of such levers, a rest, means for supporting said rest on said upper levers, and means for turning said lower pair of levers about their pivots.

12. A lifting jack comprising a base member, a pair of levers, each having spaced sides connected by webs, mounted at their lower ends to said base member, a pair of upper crossed levers, each having spaced sides connected by webs, pivotally connected at their lower ends to the free ends of the lower pair of levers, means on each upper lever intermediate its ends in slidable engagement with the other upper lever for supporting the free ends of such levers, a rest, means on said rest in slidable engagement with the upper levers for supporting said rest on said upper levers, a pair of depending arms provided on said rest and extending between said upper crossed levers, each of such depending arms having a slot therein, links pivotally mounted respectively on each of said upper pair of crossed levers, such links being pivotally connected to each other, a pin extending from the pivotal point of such links, and extending

through the vertical slots in said depending arms, and means for turning said lower pair of levers about their pivots.

13. A lifting jack comprising a base member, a pair of levers pivotally mounted at their lower ends to said base member, each lever consisting of two lever members spaced apart but rigidly connected to each other, a pair of upper crossed levers pivotally connected at their lower ends to the free ends of the lower pair of levers, each of such upper levers consisting of two lever members spaced apart and rigidly connected to each other, means on each lever member of the upper levers intermediate its ends in slidable engagement with each lever member of the other upper lever for supporting the free ends of the upper levers, a rest, means on said rest in slidable engagement with each lever member of the upper levers for supporting said rest on said upper levers, and means for turning said lower pair of levers about their pivots.

14. A lifting jack comprising a base member, a pair of crossed levers pivotally mounted at their lower ends to said base member on pivots which are spaced apart, a pair of upper crossed levers pivotally connected at their lower ends to the free ends of the lower pair of levers, means on each upper lever in slidable engagement with the other upper lever for supporting the free ends of such levers, a rest, means on said rest in slidable engagement with the upper levers for supporting said rest on said upper levers, means for turning said lower pair of levers about their pivots, and means associated with said lower pair of levers for ensuring that the said levers will move equal amounts when the means for turning them about their pivots is actuated.

15. A lifting jack comprising a pair of levers pivotally mounted at their lower ends, means for turning said levers about their pivots, a rest supported by said levers, and means intermediate said levers and said rest, whereby a substantially uniform vertical movement will be imparted to said rest for a uniform horizontal component of the movement of the upper ends of said pivoted levers, such means comprising a pair of levers pivotally connected at their lower ends to the upper ends of the first mentioned pair of levers, and supporting means on each upper lever in slidable engagement with the other upper lever for slidably supporting the free end of each lever.

16. A lifting jack comprising a pair of levers pivotally mounted at their lower ends, each lever having spaced sides connected by webs, means for turning said levers about their pivots, a rest supported by said levers and means intermediate said levers and said rest whereby a substantially uniform vertical movement will be imparted to said rest for a uniform horizontal component of the move-

ment of the upper ends of said pivoted levers, such means comprising a pair of levers each having spaced sides connected by webs, and being pivotally connected at their lower ends to the first mentioned pair of levers, and supporting means on each upper lever in slidable engagement with the other upper lever for slidably supporting the free end of each lever.

17. A lifting jack comprising a pair of levers pivotally mounted at their lower ends, means for turning said levers about their pivots, a rest supported by said levers, and means intermediate said levers and said rest comprising a second pair of levers pivotally connected to the other pair of levers, whereby a substantially uniform vertical movement will be imparted to said rest for a uniform horizontal component of the movement of the upper ends of said pivoted levers.

In testimony whereof I affix my signature. 85
